Design No. 18,503, dated August 7, 1888.

UNITED STATES PATENT OFFICE.

EDWARD H. HART, OF NEW YORK, N. Y.

DESIGN FOR A HAT.

SPECIFICATION forming part of Design No. 18,503, dated August 7, 1888.

Application filed July 2, 1888. Serial No. 278,860. Term of patent 3½ years.

• *To all whom it may concern:*

Be it known that I, EDWARD H. HART, a citizen of the United States, residing at New York, in the county and State of New York, have invented and produced a new and original Design for Hats, of which the following is a specification.

This design has for its object to provide a novel hat, as hereinafter described and illustrated in the accompanying photograph.

In the drawing, the letter A indicates the brim of the hat, and B its crown. Around the body of the hat, between the brim and the top of the crown, is draped bunting, C, containing the American or United States flag D, the emblematic colors of which are arranged in parallel zones H. Above and partly over the bunting C, at the front, are two medallions,

E E, for portraits or pictures, and upon the bunting, below the medallion, is an escutcheon, F.

Having thus described my invention or design, what I claim is—

The design for a hat having bunting C draped around the hat-body, and containing the American or United States flag D, the medallions E E, and the escutcheon F, substantially as shown and described.

In testimony whereof I have hereunto set my hand and seal in the presence of two subscribing witnesses.

EDWD. H. HART. [L. S.]
